UNITED STATES PATENT OFFICE.

DARWIN HANAUER, OF LA GRANGE, ILLINOIS, ASSIGNOR TO KINNEY ROME COMPANY,
A CORPORATION OF ILLINOIS.

SPRING-ANCHORING MEANS.

Application filed February 9, 1927. Serial No. 166,868.

In spring cushions as, for example, bed springs, made up of numerous spiral springs arranged side by side, it is customary to surround the entire structure with a frame in the form of a light rod lying approximately in the plane of the uppermost coils or turns of the springs. In some constructions the springs are tied to the frame by means of tie wires extending along the frame and having loop-like arms formed at intervals, these arms being wrapped around the frame and an adjacent portion of each spring. It is customary to lay the upper coil of each spring upon the adjacent portion of the frame and therefore, when the construction is in use and the springs are pressed down, there is a tendency to pull the springs inwardly and downwardly away from the frame; that part of a spring that is engaged by the tie wire wedging itself between the encircling arm of the latter and the frame and producing a looseness in the connection. Consequently, after a spring structure of this kind has been in use for some time, the frame is apt to be loose and it may lie at points on top of the upper coils of the springs instead of below them.

The object of the present invention is to improve the tie wire in spring structures of the kind under consideration, so as to insure that there can be no slipping of the coils of the springs relatively to the frame and no tendency to pry loose the fastenings between the springs and the frame.

The various features of novelty whereby my invention is characterized will herein-after be pointed out with particularity in the claim; but, for a full understanding of my invention and of its objects and advantages, reference may be had to the following detailed description taken in connection with the accompanying drawing, wherein:

Figure 1 is a top plan view of a fragment of a spring structure embodying my invention, showing one spring, a fragment of the frame, and a piece of the tie wire; Fig. 2 is a section taken approximately on line 2-2 or Fig. 1; and Fig. 3 is a perspective view of a fragment of the tie wire, showing one of

the securing arms before it has been wrapped around the parts to be fastened together.

Referring to the drawing, 1 represents the upper coil of a spiral spring, and 2 a fragment of the frame that surrounds the structure composed of a group of such springs arranged parallel with each other and their upper coils lying in the same plane. A section of the coil 1 lies upon the frame member and the spring and the frame are fastened together by means of a tie wire 3 that may extend along the entire length of the frame member on one side of the structure. The tie wire is bent at intervals to form laterally-extending U-shaped arms 4, as shown in Fig. 3. In accordance with my invention, I crimp each of the arms, as indicated at 5, near the closed end of the latter so as to provide the arm, on what may be termed its underside, with two concave seats spaced equal distances apart from the body portion of the wire.

In assembling a spring structure, the tie wire is laid along the frame member, underneath the upper coils of the springs adjacent to said member, with an arm projecting upwardly through each spring. This arm is then wrapped around the overlying sections of the frame and the spring as shown in Figs. 1 and 2, the crimped portions 5 forming seats to receive the wire of the spring, so that the remainder of the wire of each arm may fit closely against the frame member. Any pull on the spring or on the frame, tending to separate the two, therefore produces a direct thrust against the wire encircling the overlying portions thereof and does not tend to draw the wire of the spring into a wedge shaped space and thus produce a wedging action that will loosen the fastening.

While I have illustrated and described with particularity only a single preferred form of my invention, I do not desire to be limited to the exact structural details thus illustrated and described; but intend to cover all forms and arrangements which come within the definitions of my invention constituting the appended claim.

I claim:

In combination, a frame member, a ring lying at one side upon said frame member, a tie wire underlying the ring and extending parallel with said frame member, said wire having a portion in the form of a U-shaped arm bent upwardly through the ring and encircling the frame member and that portion

of the ring overlying the same, the members of said arm being crimped to fit upon said portion of the ring and permit the remainder of the arm to lie against the frame member.

In testimony whereof, I sign this specification.

DARWIN HANAUER.
